Inventor:

UNITED STATES PATENT OFFICE.

SARAH JANE SHIELS, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 15,498, dated October 28, 1884.

Application filed August 7, 1884. Term of patent 3½ years.

To all whom it may concern:

Be it known that I, SARAH JANE SHIELS, of the city, county, and State of New York, have invented and produced a new and original Design for a Pattern of a Lady's Costume, (numbered 9,348;) and I do hereby declare that the engraved prints accompanying this specification convey to any one accustomed to using paper patterns a clear understanding of how a garment made up by the pattern will appear.

The design shows a round walking-skirt and an overdress. The skirt exhibits the front edge of its right-side gore turned back in a revers; a plaited fan in front of the revers; a deep full left-front drapery rounding from the top of the fan to a point at the left side, and exhibiting draping plaits in its front and back edges; a short round right-front drapery that appears to widely overlap the front drapery,

and exhibits draping plaits in its front and back edges. The overdress exhibits closely-fitted basque-fronts that outline a deep point at the center, curve high over the hips, and flare from the lower edge to the tops of the shoulders over a narrow-pointed rest; a deep closely-fitted polonaise-back that exhibits underfolded plaits at the lower ends of its middle three seams, and loopings at its center and front edges, coat-sleeves, and a standing collar.

What I claim as my invention, and desire to secure by Letters Patent, is—

The design for a lady's costume, as shown in the engraved prints accompanying this specification.

SARAH JANE SHIELS.
